UNITED STATES PATENT OFFICE

SOLOMON FISHER, OF CHICAGO, ILLINOIS

DISPLAY CONSTRUCTION

Application filed January 12, 1931. Serial No. 508,192.

This invention relates to a display construction and has special reference to a panel construction for forming a background for interior, window and booth displays of merchandise.

More particularly, this invention relates to a panel comprising a sheet of rigid or self-sustaining material such as ordinary cardboard, chipboard, or the like, on which a surface facing or coating of decorative paper, foil or paint is glued or brushed, the panel being scored at spaced intervals alternately on opposite sides thereof either regularly or irregularly to outline a series of pleats into which the panel may be organized.

Perhaps the greatest concern of producers of advertising displays is the delivery and installation thereof. After a window or other display has been constructed according to the present standards, the same is crated in a large cumbersome crate for preservation in handling. If the display is of substantial dimensions, it is built in sections for convenience in handling although this manner of construction is undesirable owing to the necessary unsightliness of piecing the parts together at the place of installation. The bulkiness of the shipment, of course, adds considerably to the cost of handling.

It is one of the objects of this invention to provide a panel construction which may be so arranged when several units are assembled that no seam or edge is seen where the units are fastened together. The accordion pleated panels, as one form will be called hereinafter, are formed by scoring at spaced intervals alternately on opposite sides of the panel and present, when properly folded, a series of pleats preferably in an odd number to resemble the folds of the bellows part of an accordion. Also, the folds may be irregularly scored on opposite sides to form box pleats or alternately box and accordion pleats, or other variations. The last pleat at one end of a panel extends in a direction away

from the observer to overlap and thereby to exclude from sight the forwardly extending pleat at the other end of the adjacent panel. The connection of the two panels merely gives the appearance of the line of fold as is found in the other pleats.

It is a further object of this invention to provide a panel construction in which any number thereof may be attached together as one for any length of background or booth, the panels being capable of being folded like an accordion to occupy but a minimum of space and to obviate the necessity of providing a package for preservation in handling. In this connection it is to be noted that each panel is six or seven feet high and twenty-six inches wide when in an extended condition and but approximately one by two inches by the same height when prepared for shipping or storage.

As noted above, the preparation of the background for delivery and the actual delivery thereof may be accomplished with a minimum of time, expense and inconvenience. It is also an object of this invention to provide a panel of the character noted above which may be easily installed. The material of the panel we have already recited is of ordinary cardboard, chipboard or of like materials which are light and therefore easily handled and worked. Almost unlimited ideas may be worked out into backgrounds with a pair of shears, a knife, and a sheet of pins.

Another great difficulty in the usual backgrounds on the market today lies in the warping of the panels. A single sheet of cardboard or the like when stood on end invariably warps unless provided with a stiffener in the form of a wooden frame or of like means. In the present invention the construction of the panel is such as to prevent warping in any direction without the use of separate means which will be readily apparent from the drawings. From the artistic point of view,

the pleated panels give a depth to the background not to be had in the usual displays which have plain surfaces and are, therefore, flat and without depth. The pleated panels 5 have that function of reflecting highlights and shadows.

A still further object of this invention is to provide a panel construction as indicated above which is inexpensive to manufacture, 10 15 20

is attractive in appearance, and is durable.

Again, it is the object of this invention to provide a panel construction of the type referred to above which may be self-supporting.

Other objects and advantages will herein- 15 20 25 30 35 40

after be more particularly pointed out and for a more complete understanding of the characteristic features of this invention reference may now be had to the following description when taken together with the accom- 20 25 30 35 40

panying drawings, in which latter:

Figure 1 is a front elevational view of a window display employing a series of panels of the type as taught by the present invention;

Fig. 2 is a perspective view of several 25 panels connected together;

Fig. 3 is a group of panels showing several of the decorative effects which may be produced at the upper ends thereof;

Fig. 4 is a perspective view of a panel, the 30 35 40 ends of which are secured together to form a self-supporting base;

Fig. 5 is a view similar to Fig. 4 showing the panel arranged into a configuration somewhat different than that shown in Fig. 4;

Fig. 6 is a perspective view of a panel when 35 40 45 50 55 60 65 70 75 80 85 90 95 100 105 110 115 120 125 130

folded into a package for shipment or storage;

Fig. 7 is a side elevational view of a portion of a panel showing the same after it 40 45 50 55 60 65 70 75 80 85 90 95 100 105 110 115 120 125 130

has been scored;

Fig. 8 is a side elevational view of a portion of the panel shown in Fig. 7 showing the material between the scored portions as being folded alternately backward and forward to resemble the folds of the bellows part of an accordion;

Fig. 9 is a view similar to Fig. 8 showing a positioning member for the pleats;

Fig. 10 is a view similar to Fig. 9 although 50 55 60 65 70 75 80 85 90 95 100 105 110 115 120 125 130

substantially reduced showing a modified form of positioning means;

Fig. 11 is a sectional view similar to Fig. 10 showing still another form of positioning means; and

Fig. 12 is a perspective view of one of the panels showing an easel support secured to the pleat positioning member.

Referring now to the drawings, and more particularly to Fig. 7 thereof, the device of 60 65 70 75 80 85 90 95 100 105 110 115 120 125 130

this invention comprises a sheet 15 of rigid or self-sustaining material such as the usual cardboard or chipboard. It may be desirable to finish the rear side of the chipboard by gluing thereto a piece of ordinary paper 65 16 merely to cover the cardboard or chip-

board to a more pleasing appearance to the backside of the panel. A sheet of decorative paper or foil 17 may be glued on the front side of the panel to give the decorative effect for which the background is employed, although, it will be noted that a coating of paint, gilt, or the like, may be employed perhaps as effectively as any other decorative material.

After the cardboard or chipboard 15 has been surfaced or coated, the sheet which is six or seven feet long and about twenty-six inches wide is preferably run through a machine having rotary blades to score the panel in a lengthwise direction to produce weakened portions having a line of fold for the pleats. The score marks 18 on the face side of the panel are disposed about four inches apart and the score marks 19 on the opposite side of the panel are placed the same distance apart although intermediate the score marks 18.

The scoring thus provided readily permits the formation of pleats folded in a manner to resemble the folds of the bellows part of an accordion, the one fold being forwardly and the next fold rearwardly throughout the length thereof. This construction, of course, may be varied at will to produce different effects. Inasmuch as the panel is twenty-six inches wide, the score marks will set off or outline exactly 13 pleats. It is preferable to employ an odd number of pleats for the reason that in an organization of several panels there will be no seam or edge exposed when they are fastened together, as will be more particularly noted with reference to Fig. 2 hereinafter described more fully.

Referring now more particularly to Fig. 8, it will be noted that the scored panel of Fig. 7 has been folded to produce an accordion pleated panel, two of the pleats, when taken together, being organized into a V-shape or inverted V-shape depending upon the combination selected. This results in the formation of a base upon which the panel may rest so that each panel is self-supporting except, of course, as against unnatural forces. A panel twenty-six inches wide, when in the condition shown in Fig. 7, should cover a space of about twenty inches in width when in the condition shown in Fig. 8. However, referring more particularly to Fig. 6, the same panel, when prepared for shipping or storing, may be folded into a package that is two inches in one direction, that is, the width of the pleats, by about one inch wide, that is, the total thicknesses of the pleats, the panel being six or seven feet long. This makes an extremely convenient and economical package to handle, to ship, and to store.

For decorating a show window twenty-two feet long requiring about fifteen panels for background material, the entire number of panels could be shipped in a package five 130

by six inches, by six or seven feet long. There is no necessity for crating the panels for preservation in handling or for convenience in handling. There is no substantial bulk and the package would require but a minimum of expense to ship. Being made of cardboard and the like over which a coating of inexpensive decorative paper may be employed, the panel may be manufactured for a minimum amount. By reason of the fact that any desired type of decorating may be done on the panel, as attractive an appearance may be produced as could result from any background which may be manufactured. Also, inasmuch as the device is made of a rigid or self-sustaining material the panel is very durable.

In order to more definitely position the pleats in a single plane and also in order to hold the pleats in substantially the same angle with respect to each other that the background may be symmetrical, a heavy paper or fabric tab 20 may be fastened on the rear side of two adjoining pleats, that is, one end 25 of the tab may be glued or otherwise secured to one pleat adjacent the scoring and the other end of the tab may be secured in a like manner to an adjoining pleat adjacent the scoring. A loop or surplus of material in such 30 a case is left between the fastened ends of the tab through which apertures are formed to receive a rod 21, which latter may be of sufficient length to position several panels. Any 35 desired number of tabs 20 may be employed, it being noted that in Fig. 9 each rear formation is provided with a tab whereas it may only be desirable to provide a tab for every other or every third or more rear formation. The outer end of the panel or the last pleat 40 may have a tab, both ends of which latter are fastened to the one end of the pleat.

Referring now more particularly to Fig. 10, it will be noted that the tabs 20 have fastened thereto a cord 22 in place of the rod 45 21. This is a modified form and may be desirable in instances of use where the panel effects a circular or curvilinear background.

We have hereinbefore shown the use of a 50 positioning means comprising tabs through which or into which other means have been secured, although, it may be desirable to eliminate the tabs and merely provide apertures in the pleats of the panel itself, such as is shown in Fig. 11, the apertures 23 receiving either a rod 24 or a cord, which latter is not 55 shown. A positioning member such as this may be desired in many instances and would, of course, be less expensive to manufacture than the construction heretofore illustrated 60 and described. However, in the latter instance, the rod or cord is exposed to view and would preferably be of some decorative effect and of a color to either form a direct contrast or to become absorbed in the background.

65 We have heretofore expressed a quality of

the panel construction as being that of supporting itself by reason of its V-shaped cross section. We have qualified this statement by saying that it is self-supporting except against unnatural forces. In order, therefore, to make the construction fool-proof, an 70 easel support 25 may be hinged or otherwise fastened to the rod 21 or to a portion of the panel for preventing the displacement of the panel by unnatural forces. In such an event 75 but a single easel support 25 may be provided for one section whereafter all of the other units in the organization of the background are likewise supported thereby.

Referring now more particularly to Fig. 4, 80 a panel is shown in which the longitudinal ends thereof are fastened together to form a supporting base on which may be placed articles for display. The ends may be fastened together by the usual clips or pins, the contour of the support being of any desired shape to harmonize with the background. For example, in Fig. 4, a star-shaped cross section 85 may be produced. In Fig. 5, the same supporting member has been reorganized into an elongated shape which may be more desirable with other settings. These supports may be provided in any desired heights and are of sufficient strength to support great 90 weights. 95

Referring now more particularly to Fig. 3, it will be noted that various decorative effects may be obtained by merely trimming the upper end to harmonize with the setting desired. All of these effects may be obtained with a 100 pair of shears inasmuch as the material of the panel is of cardboard, the effects obtainable being limited only by the individual's ideas.

The panels are fastened together as one for 105 any length of background. It is impossible to note where the panels are fastened together because no seam or edge is exposed. Referring now more particularly to Fig. 2, five panels are shown fastened together, the two end panels being directed at an angle 110 to the three intermediate panels. It will be noted that the last pleat 26 at one end of a panel extends in a direction away from the observer to overlap and thereby to exclude 115 from sight the forwardly extending pleat of the other end of the adjacent panel. The connection of the various panels, therefore, merely gives the appearance of a line of fold which is found several times in all of the pleats. Thereby the necessary unsightliness 120 of piecing the parts together as in the standard displays on the market today is avoided. The installation of the panels is, of course, very simple, the overlapping pleats being merely fastened together by cleats, pins, or 125 in any other manner to which the average layman may readily adapt himself.

A sample display window is shown in Figure 1 in which units are organized into a single 130 background having the effect of a single

sheet of material. Ordinarily, this background being of approximately twelve feet in length would have to be fabricated at the manufacturers in several sections, placed in 5 crates and shipped under substantial expense to its destination whereafter the sections would have to be uncrated and pieced together. In standard constructions the piecing together of the sections to form a single 10 continuous background is usually unsightly owing to the fact that the continuity of the picture or other representation is broken. The uniformity of the present construction eliminates the possibility of the continuity 15 being broken. In the present instance, the background may be shipped in a single package uncrated and merely tied together with a string. The weight is slight and the entire display could be very easily carried by a single 20 messenger boy with little inconvenience, the package including the six pieces of varying heights shown more particularly in Figs. 4 and 5, together with the positioning means. Any decorative effect may be obtained 25 whether it is a picture or merely another decorative effect obtained by paper or paint. The heights of the panels and the shapes thereof may be varied to accommodate any desired setting.

30 As a result of this invention, a background of any desired length may be formed of a great number of units having the appearance of a single panel, there being no seams or edges exposed to sight when the various units 35 are fastened together. The panels may be kept in stock and sold at a minimum of expense owing to the fact that they may be produced in quantity production and ordered directly from stock for any type installation.

40 The material of the panels is such that it may be readily formed into any desired shape merely with the use of a pair of shears. The panels may be organized into backgrounds of great length by securing means commonly 45 known to the average layman, such as pins, clips, and the usual paper fasteners. Any desired decorative effect may be obtained owing to the unlimited possibilities with which the background material may be treat- 50 ed. Various surfacings or coatings may be disposed on the cardboard stock. The panels may be folded so as to occupy but a minimum of space and thereby reduce the expense in handling and reduce the space 55 required for storage. There is no likelihood of the panels becoming mutilated or destroyed even though they are not crated or otherwise preserved for handling. The panels 60 are prevented from warping owing to the V-shaped cross section thereof. The panels twenty-six inches in width may be folded into a package one by two inches and a sufficient number of these small packages or 65 ganized into a bundle five by six inches square

for accommodating the usual entire window display.

It will be understood that the above dimensions are merely for illustrative purposes and that the shapes and materials employed may be modified by those skilled in the art without departing from the spirit and scope of this invention, and, therefore, the same is to be limited only by the scope of the prior art and the appended claims.

I claim:

1. A display construction comprising a pleated panel, and separate means associated with said pleats to determine the positions thereof.

2. A display construction comprising a pleated panel, and a rod for engagement with a plurality of said pleats to determine the positions thereof.

3. A display construction comprising a pleated panel, and a rod for determining the positions of said pleats, said panel having means in which said rod is detachably connected.

4. A display construction comprising a pleated panel, and a rod for determining the positions of said pleats, said panel having registering apertures in the pleats thereof through which said rod is inserted.

5. A display construction comprising a pleated panel, tabs secured to a plurality of said pleats, and means for connecting said tabs for determining the positions of said pleats.

6. A display construction comprising a pleated panel, tabs secured to a plurality of said pleats, said tabs having apertures therein, and means for engaging said apertures to determine the positions of said pleats.

7. A display construction comprising a pleated panel, and a cord secured to a plurality of pleats thereof to determine the positions of the pleats of said panel.

8. A display construction comprising a pleated panel having the ends thereof fastened together to form a standard for supporting an object.

9. A display construction comprising a plurality of assembled units of pleated panels, said panels consisting of an odd number of pleats whereby one end pleat extending in a direction away from an observer overlaps an adjacent end pleat extending in a direction toward the observer in order that no edge or seam is seen when the units are assembled.

10. A display construction comprising a plurality of assembled units of pleated panels, each of said panels being scored alternately on opposite sides thereof to provide weakened portions for forming lines of fold for said pleats, the end pleats of adjacent intermediate panels overlapping in a manner such that the overlapping pleat extends in a direction away from the observer
